UNITED STATES PATENT OFFICE.

CHARLES H. JAMES, OF WABASH, INDIANA, ASSIGNOR, BY DIRECT AND MESNE ASSIGNMENTS, OF TWO-THIRDS TO FRANCIS H. LOWRY AND GEORGE W. BLAIR, BOTH OF SAME PLACE.

WEATHER-STRIP.

SPECIFICATION forming part of Letters Patent No. 368,151, dated August 9, 1887.

Application filed December 30, 1884. Renewed January 3, 1887. Serial No. 223,816. (No model.)

To all whom it may concern:

Be it known that I, CHARLES H. JAMES, a citizen of the United States, residing at Wabash, in the county of Wabash and State of Indiana, have invented certain new and useful Improvements in Weather-Strips, of which the following is a specification, reference being had to the accompanying drawings.

My invention consists in providing a weather-strip with curved flat-metal guards, adapted to be embedded into the strip without nails or screws, in such a manner as to protect the ends of the strip from wear or injury.

In the accompanying drawings, Figure 1 is a rear view in perspective of the improved weather-strip detached from the door. Fig. 2 is a cross-section of the same when attached to a door. Fig. 3 is a front view in perspective of one end of the weather-strip, and Fig. 4 is a detail view of a guide-piece used in connection with weather-strip.

A represents a door, and B represents a molding, which is applied to the lower side of the door in the usual manner, and which is rabbeted on its lower side, as at C. To the lower side of the tongue D is pivoted a strip, E, by means of staples F. Flat springs G are placed in the rabbeted portion of the molding and bear against the upper edge of the pivoted strip and serve to keep said strip normally in position. (Shown in solid lines in Fig. 1.)

In order to limit the movement of the strip, I secure depending U-shaped keepers H to the rear sides of the molding and hooks I to the upper edge of the pivoted strip. These hooks project into the keepers and bear against the curved lower portions of said keepers when the door is open and the strip is in its normal position. The keepers are arranged centrally in relation to the springs, and serve to prevent the springs from being displaced.

In Fig. 3 I illustrate a guard-strip, which I secure on the ends of the weather-strip for the purpose of preventing wear. These guard-

strips K are bent so as to conform to the shape of the weather-strip, and are provided with curved hooked ends, which are embedded in the ends of the strip. This construction of the guard-strips enables them to be applied to the weather-strip without the use of nails or screws. Fig. 4 illustrates a curved metal guide, which is secured to the casing or sill of door-frames. It is curved and angular.

The operation of the device is as follows: When the door is opened the spring G, acting on the rear portion of the strip E, raises the forward end thereof, and so prevents it from coming in contact with the floor or sill during the swinging of the door. The hooks I, moving in the guide-keepers H, permit the free movement of the strip E on its hinges, and also limit the upward movement of the forward edge of the strip. When the door is closed the metal guard-strips K on the ends of the strip come in contact with the curved guide-pieces L on the casing, which turn the strip downward, so as to close the crack beneath the door.

Having thus described my invention, I claim—

The molding B, attached to a door, said molding being rabbeted or hollowed out on its lower side next the door, and a weather-strip, E, hinged to the lower part of the molding and extending beneath the hollowed part thereof, in combination with springs G, located in the hollowed part of the molding and bearing against the weather-strip, guide-keepers H, supported by the molding, and hooks I, attached to the strip, which co-operate with said keepers to limit the movement of the strip, substantially as set forth.

In testimony whereof I affix my signature in presence of two witnesses.

CHARLES H. JAMES.
